UNITED STATES PATENT OFFICE

CLARENCE WILLIAMS AND ERNST G. APPLETON, OF CHICAGO, ILLINOIS, ASSIGNORS TO
ROACH-APPLETON MANUFACTURING COMPANY, OF CHICAGO, ILLINOIS, A CORPOR-
ATION OF ILLINOIS

THREE POSITION TOGGLE SWITCH

Application filed March 10, 1928. Serial No. 260,720.

The present invention relates to improvements in three position toggle switches.

More particularly the present invention relates to improvements in switches in which it is desired to have three distinct positions, as for example, an open circuiting position and two alternative circuit making positions.

An object of the present invention is to provide an improved toggle switch for three distinct positions which is small, sturdy and not likely to get out of order.

A further object is to provide a three position toggle switch which is simple and cheap to assemble and which may be made up for the most part of metal stampings.

A further object is to provide a small three position toggle switch which is well adapted to meet the needs of commercial operation.

20 Further objects will appear as the description proceeds.

Referring to the drawings—

Figure 1 is a view in side elevation of one embodiment of the present invention;

25 Figure 2 is an end view of the switch showing the terminals thereof;

Figure 3 is a sectional view taken along the plane indicated by the arrows 3—3 of Figure 2, said view illustrating the parts 30 in mid or open circuit position;

Figure 4 is a view similar to Figure 3 but illustrating the parts in one of the two alternative circuit making positions;

Figure 5 is a sectional view taken along the plane indicated by the arrows 5—5 of Figure 3;

Figure 6 is a sectional view taken along the plane indicated by the arrows 6—6 of Figure 5; and

40 Figure 7 is a perspective view.

The numeral 10 indicates a cup shaped member which may be swaged from sheet metal. The outer wall of 11 of said cup shaped member 10 is provided with an aperture

45 12 which if preferred may be bounded by the eyelet 13 which presents, at least inwardly of the cup shaped member 10, a rounded, smooth surface. Said eyelet 13 provides a bearing for the ball portion 14 of the finger hold 15 which projects through

the aperture provided by the eyelet 13. Disposed within the cup shaped member 10 is the sheet metal member 16 which comprises the concave portion 17 and the leg portions 18—18. Said sheet metal member 16 fits more or less closely within the cup shaped member 10, and the legs 18—18 project substantially to the plane of the rim of the cup shaped member 10. The illustrated embodiment of the present invention 55 includes a cup shaped member 10 which is substantially oblong in cross section. In the particular embodiment chosen for illustration four legs 18—18 are provided. The rim of the cup shaped member 10 is abutted by the cover 19 which may be composed of insulating material, such, for example, as fiber. Said cover 19 is adapted to abut the extremities of the legs 18—18 whereby the concave portion 17 of the sheet metal member 16 is held in predetermined position 60 within the cup shaped member 10. Said concave portion 17 of the sheet metal member 16 is provided with the aperture 20 for receiving the extremity of the finger hold 65 15, the rim defining said aperture providing a bearing for the ball portion 14. It will be understood that when the cover 19 is in place, upon the cup shaped member 10, the sheet metal member 16 will be held in 70 such a position that the concave portion thereof will abut against the ball portion 14 of the finger hold 15, limiting inward movement of the finger hold 15. Outward movement of the finger hold 15 will, of course, 75 be prevented by the eyelet 13. The rim of the cup shaped member 10 is provided with fingers 21—21 fitting within slots 22—22 in the edge of the cover 19. The extremities of said fingers 21—21 may be bent over 80 upon the cover 19 whereby to hold said cover securely in place relative to said cup shaped member 10.

The insulating cover 19 has three apertures 85 23—23 extending therethrough, each adapted to receive a projecting portion 24 of a terminal 25. The three terminals 25—25 may be identical, and the projecting portions 24 thereof may be internally screw-threaded for the reception of a headed screw 90 100

(not shown) to permit the attachment of an electric wire to each of said terminals. Disposed on the inner side of the insulating cover 19 are three contact members for co-operation with the three terminal members 25-25. The middle contact member on the inner side of the insulating cover 19 is indicated by the numeral 26. Said contact member 26 is mechanically and electrically united to the middle terminal member 25, said union being accomplished by means of tongues not shown extending from the corresponding terminal 25 through suitable apertures, which tongues are riveted over the inner surface of the contact member 26. Said contact member 26 is in the form of a yoke having the two arms 27-27, adjacent sides of said arms being notched as indicated by the numerals 28-28 to rockingly support the rocking member or cradle 29, which cradle 29 will be described presently. Arranged on either side of the middle contact member 26 in position to be selectively contacted by the cradle 29 are the contact members 30-30, each of which is mechanically and electrically united to one of the outer terminal members 25-25. Said union is accomplished by means of tongue 31 projecting from the corresponding terminal members 25-25 which tongues extend through suitable apertures and have their extremities riveted over upon the inside surfaces of the contact members 30-30. Said riveted over extremities are indicated by the numerals 32-32 in Figure 5. The contact members 30-30 are spaced from the contact member 26 a sufficient distance to insure that there will be no direct electrical connection between said contact members. However, the present invention contemplates a construction in which the cradle 29, which is rockingly supported by the contact member 26, may engage with one or the other of the contact members 30-30 in order to provide an electrical connection between the middle terminal 25 and one or the other of the two outer terminals 25-25. Moreover, the present invention contemplates a construction in which the cradle 29 may be held in mid position out of contact with either of the contact members 30-30.

Extending longitudinally of the finger hold 15 is the hole 33 closed at the outer extremity of said finger hold and open at the inner extremity of said finger hold. Disposed in the open end of said hole 33 is the operating pin 34, preferably of insulating material, the outer end of which pin is rounded. A spring 35 is disposed within the hole 33 and tends to urge the pin 34 outwardly. The cradle 29 has the wings 35a each having the notch 35b. Said notches are symmetrically disposed relative to the length of the cradle 29. Said notches 35b-35b receive the upper portions of the arms

27-27 outwardly of the notches 28-28. The wings 35a-35a, between the notches 35b-35b rest upon the notched portions of the arms 27-27. The contact member with its arms 27-27 therefore form a fulcrum for the cradle 29.

The cradle 29 is provided along a line transverse to the axis of swing of said cradle with a groove 36 for receiving the rounded extremity of the pin 34. Disposed at the ends of said groove 36 are the walls 37-37 adapted to be abutted by the rounded extremity of the pin 34. Cradle 29 is provided with a socket 38 for receiving a rounded extremity of the pin 34 which socket is disposed midway between the walls 37-37 defining the ends of the groove 36. Said socket 38 is disposed symmetrically with reference to the axis of swing of the cradle 29, whereby when the parts are in the position illustrated in Figure 3, the spring 35 will have no tendency to swing the cradle 29 to either one side or the other of its axis of swing. On the other hand, by reason of the engagement of the rounded end of the pin 34 within the socket 38, the cradle 29 will be positively held in its mid position.

It will be readily observed that the improved switch is made up of parts which are simple and inexpensive to manufacture. The finger hold may be readily inserted through the eyelet 13 by inserting the outer end of said finger hold through said eyelet after which the member 16 may be inserted. By reason of the fact that the member 16 fits more or less closely within the cup shaped member 10, said member 16 will permit the convenient handling on a commercial basis of a unit comprising the cup shaped member 10, finger hold 15 and member 16. The terminals 25-25 and the contact members 26 and 30 may be readily secured to the insulating cover 19, and the cradle 29 may be disposed upon the arms 27-27 in a very simple operation. After the spring 35 and pin 34 have been placed within the finger hold 15, the parts may now be placed together with the insulating cover 19 in position upon the rim of the cup shaped member 10, after which the fingers 21-21 may be bent over to hold the parts securely in place.

Inasmuch as when the finger hold 15 is in its mid position it exerts a holding force symmetrically disposed relative to the axis of swing of the cradle 29, said cradle 29 will be positively held in mid position until a positive force is exerted upon said finger hold 15 to move same with an angular movement. An angular movement of the finger hold 15 one way or another relative to the axis of swing of the cradle 29 will result in the compression of the spring 35 sufficient to free the pin 34 from the socket 38 after

which said spring will expand to urge the cradle 29 with a snap action of the one or the other of its contact making positions. Similarly, when it is desired to move the

5 cradle 29 out of one of its contact making positions, no tendency to move the cradle 29 will occur until sufficient force has been applied to the spring 35 to snap the pin 34 either into the socket 38 or into the other 10 extremity of the groove 36. The making and breaking of contact will, therefore, be accomplished with a snap action.

Though a preferred embodiment of the present invention has been described in detail, many modifications will occur to those skilled in the art. It is intended to cover all such modifications that fall within the scope of the appended claims.

We claim:

20 1. In a switch, in combination, a cup-shaped member having an aperture in the bottom wall thereof, a member of sheet material fitting within said cup-shaped member and having an aperture in substantial 25 alignment with said first-mentioned aperture, an operating member disposed within said apertures and having a protuberance rotatably seated between said member of sheet material and the bottom of said cup-shaped 30 member in bearing relationship with said member of sheet material and said bottom. 35 2. In a switch, in combination, a cup-shaped member having an aperture in the bottom wall thereof, a member of sheet material fitting within said cup-shaped member and having an aperture in substantial 40 alignment with said first-mentioned aperture, an operating member disposed within said apertures and having a protuberance rotatably seated between said member of sheet material and the bottom of said cup-shaped 45 member, said cup-shaped member having an insulating closure, and abutment means cooperating with said closure for holding said member of sheet material in predetermined position relative to said protuberance.

50 3. In a switch, in combination, a cup-shaped member having an aperture in the bottom wall thereof, a member of sheet material fitting within said cup-shaped member and having an aperture in substantial 55 alignment with said first-mentioned aperture, an operating member disposed within said apertures and having a protuberance rotatably seated between said member of sheet material and the bottom of said cup-shaped member, said cup-shaped member having an insulating closure, and abutment 60 means cooperating with said closure for holding said member of sheet material in predetermined position relative to said protuberance and a plurality of terminals carried by said closure member, one of said 65 terminals comprising a fulcrum, a rocking

member electrically connected to said one terminal member, said operating member being provided with spring-projected means for selectively biasing said rocking member to one side or the other of its fulcrum.

70 4. In a switch, in combination, a cup-shaped member having an aperture in the bottom wall thereof, a member of sheet material fitting within said cup-shaped member and having an aperture in substantial 75 alignment with said first-mentioned aperture, an operating member disposed within said apertures and having a protuberance rotatably seated between said member of sheet material and the bottom of said cup-shaped member, said cup-shaped member having an insulating closure, and abutment means cooperating with said closure for holding said member of sheet material in predetermined 80 position relative to said protuberance, said closure member being provided with a plurality of terminals, one of said terminals providing a fulcrum, a rocking member in electrical contact with said fulcrum and having a socket symmetrically disposed relative 85 to said fulcrum, said operating member including a spring-projected insulating member adapted to be seated within said socket to hold said rocking member in mid position or to selectively bias said rocking member to one side or the other of said fulcrum.

90 Signed at Chicago, Illinois, this 5th day of March, 1928.
